(57) **CLAIM**

The ornamental design for a wearable fishing rod holder, as shown and described.

DESCRIPTION

FIG. 1 is an isometric view of a wearable fishing rod holder showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is a rear elevational view thereof; and,

FIG. 8 is an isometric operational view thereof showing my design.

The broken lines in FIG. 8 depict environmental features that form no part of the claimed design. The broken lines in FIGS. 2 and 7 depict parts of the wearable fishing rod holder that form no part of the claimed design.

1 Claim, 5 Drawing Sheets
